UNITED STATES PATENT OFFICE.

WILLIAM P. HALL, OF INDIANAPOLIS, INDIANA, ASSIGNOR TO ONE-PIECE BIFOCAL LENS COMPANY, OF INDIANAPOLIS, INDIANA, A CORPORATION OF INDIANA.

LENS-GRINDING TOOL.

1,162,053.

Specification of Letters Patent. Patented Nov. 30, 1915.

Application filed July 20, 1914. Serial No. 851,950.

To all whom it may concern:

Be it known that I, WILLIAM P. HALL, a citizen of the United States, and a resident of Indianapolis, county of Marion, and State 5 of Indiana, have invented a certain new and useful Lens-Grinding Tool; and I do hereby declare that the following is a full, clear, and exact description thereof, reference being had to the accompanying drawings, in 10 which like letters refer to like parts.

This invention has been made with particular reference to grinding one piece bifocal lenses, but is not limited to the grinding of said one class of lenses as they may be 15 used for making other lenses.

The object of this invention is to maintain a uniform curvature of the grinding surface of the tool or wheel, whether spherical or toric, during the life of the tool, and thus 20 with all adjustments by way of expansion, to provide for the changes resulting from usage. To that end the tool is arranged so that it can be expanded as worn and the same diameter always be maintained. After 25 each period of wear, the tool is expanded and the grinding surface refinished so that after such readjustment, the curvatures of the grinding surfaces, both circumferentially and transversely, remain the same as before 30 wear and adjustinent.

The chief feature of the invention consists in forming the grinding surface of segments of grinding material and as the segments are expanded, the gaps between 35 the segments are filled with pitch or other grinding material, so as to make a homogeneous grinding surface.

The full nature of the invention will be understood from the accompanying drawings and the following description and 40 claims.

In the drawings, Figure 1 shows one-half of the grinding tool in elevation and the other half in central circumferential section. 45 Fig. 2 is a transverse section on the line 2—2 of Fig. 1. Fig. 3 is substantially the same as the right hand half of Fig. 1, with the grinding segments expanded. Fig. 4 is a section on the line 4—4 of Fig. 3. Fig. 5 is 50 an elevation of the right hand portion of the device as shown in Fig. 3.

Said grinding tool consists of a hub portion 10 which is adapted to be mounted on a suitable shaft, not shown, and which on

one end has a radially extending disk 11 55 with an inwardly extending annular rim plate 12 concentric with the hub 10 so as to leave a space 13 surrounding the hub to the inner side of the disk 11. The outer end of the hub 10 is externally threaded at 14 to 60 receive a sleeve 15 which screws thereon and has an inner reduced portion 16 and a still further inward tapering or cone-like portion 17 snugly surrounding the hub.

The disk 11 extends radially beyond the 65 rim-like plate 12 so as to form a peripheral chamber 20 in which segmental plates 21 are located end to end. In the form herein shown there are four such plates and each plate has an arm 22 which extends inwardly 70 through a suitable opening 23 in the rim 12 to the beveled or inclined cone-like portion 17 of the wedging sleeve 15. The inner ends of the arms 22 are turned, as indicated in Figs. 1 and 2, so as to fit snugly on the inclined surface 17. The purpose of this arrangement is to enable the arms 22 and their plates 21 to be forced radially outward by 75 screwing in the sleeve 15 and to be thereby maintained in their outward positions. 80

Each segmental plate 21 has secured upon its outer surface a body 25 of grinding material or some material which will retain an abrasive substance on its periphery, and it is held in place on said plate by a clamping rod 26 extending transversely through the same and through a radial slot 27 in the outer portion of the disk 11 and through a radial slot 28 in an annular ring 29 which surrounds the rim 12. Said ring 29 is located opposite to and corresponds with the outer portion of the rim 11 and the bolt 26 has nuts on each end whereby the ring 29 is clamped against the segmental grinding body 25 and thus it is clamped against the 90 outer portion of the disk 11. 95

When first assembled, the plates 21 and grinding segments are bound together, abutting against each other, as shown in Fig. 1, and the outer surfaces ground to the desired 100 curvatures, circumferentially as well as transversely. As the outer surfaces wear, the sleeve 15 is screwed inward farther and farther so as to force the segments 25 outward and enable them to be refinished to the 105 same diameter as before. This can be continued until the grinding segments are practically used up and then they may be re-

moved and new grinding segments 25 substituted. With this arrangement, the grinding segments 25 may be made of some normally soft material such as pitch because they are held securely in place; and, as the segments are expanded, the gaps at 30, see Figs. 3 and 5, are filled with pitch or other grinding material of the same general character as the grinding segments. This maintains a smooth grinding surface between the segments and uniform with the segments. These gaps, however, do not become very great and need not at the most exceed a quarter of an inch in thickness. When the tool is expanded, the gaps are filled and then the wheel is refinished as stated to obtain the original curvatures. Hence, this tool is adapted to be used at all times for grinding a uniform surface upon all the lenses.

20. The invention claimed is:

1. A lens grinding tool including a rotatable hub portion, a series of segmental plates radially expansible on said hub portion, abrasive retentive material secured upon said segmental plates and means for simultaneously expanding said segments.
2. A lens grinding tool including a rotatable hub portion, segments made of suitable grinding material mounted expansively upon said hub portion, centrally located means for simultaneously expanding said segments and grinding material filling the gaps between said segments when expanded.
3. A lens grinding tool including a rotatable hub portion, a series of segmental plates radially expansible on said hub portion, a segment of grinding material secured upon each segmental plate, and suitable grinding material filling the gaps between the segmental plates and segments of grinding material when expanded.
4. A lens grinding tool including a rotatable hub, a series of segmental plates mounted on said hub so as to be radially expanded, segments of grinding material secured on said segmental plates, annular plates beside said segments immovable with relation to the hub and radially slotted, and clamping bolts extending through said segments and the slots in said side plates.
5. A lens grinding tool including a rotatable hub, a series of segmental plates mounted on said hub so as to be radially expanded, segments of grinding material secured on said segmental plates, annular plates beside said segments immovable with relation to the hub and radially slotted, clamping bolts extending through said segments and the slots in said side plates, and

a single means for radially expanding all of 60 said segmental plates.

6. A lens grinding tool including a rotatable hub, an annular rim rigid with and surrounding and spaced from said hub, segmental plates on the periphery of said rim, 65 arms secured to said plates and extending radially inward through holes in said rim, a sleeve adapted to screw on said hub and having an inner beveled surface adapted to engage the arms of all of the segmental 70 plates and simultaneously expand said plates, and grinding material secured upon said segmental plates.

7. A lens grinding tool including a rotatable hub, an annular rim rigid with said 75 hub and surrounding and spaced from the same, segmental plates on the outer surface of said rim, arms extending from said segmental plates radially inward through holes in the rim, means for simultaneously acting 80 on said arms for radially expanding said segmental plates, grinding material secured on said plates, a radial ring rigid with said rim and located at one side of said segmental plates and grinding segments, a radial ring 85 at the other side of said segmental plates and grinding segments and surrounding said rim, said rings having radial slots, and clamping bolts extending through the grinding segments and the slots of said rings. 90

8. A lens grinding tool including a rotatable hub, an annular rim rigid with said hub and surrounding and spaced from the same, segmental plates on the outer surface of said rim, arms extending from said segmental plates radially inward through holes in the rim, grinding material secured on said plates, a radial ring rigid with said rim and located at the side of said segmental plates and grinding segments, a radial ring 100 at the other side of said segmental plates and grinding segments and surrounding said rim, said rings having radial slots, clamping bolts extending through the grinding segments and the slots of said 105 rings, and a sleeve adapted to be screwed on said hub with its inner surface beveled to engage corresponding beveled edges of the arms from said segmental plates for radially expanding them and the grinding segments. 110

In witness whereof, I have hereunto affixed my signature in the presence of the witnesses herein named.

WILLIAM P. HALL.
